UNITED STATES PATENT OFFICE.

MICHAEL C. TAYLOR, OF SAN FRANCISCO, CALIFORNIA.

GUN-MOUNT.

No. 802,123.

Specification of Letters Patent.

Patented Oct. 17, 1905.

Application filed September 6, 1904. Serial No. 223,405.

To all whom it may concern:

Be it known that I, MICHAEL C. TAYLOR, a citizen of the United States, residing in the city and county of San Francisco and State of California, have invented new and useful Improvements in Gun-Mounts, of which the following is a specification.

My invention relates to a gun-mount and firing apparatus.

It consists in a combination of mechanism whereby a battery of guns is mounted, manipulated, and fired in unison and in details of construction, which will be more fully explained by reference to the accompanying drawings, in which—

Figure 1 is a perspective view of my apparatus. Fig. 2 is a longitudinal vertical section of same.

The apparatus may be carried upon a stationary mount, or, as shown in the present case, it may be mounted upon a movable carriage, as A.

2 is a shield sufficiently open at the rear and convergent at the front so as to present inclined surfaces for the impact of hostile projectiles. This shield is made of a length sufficient to accommodate as many guns 3 as it may be desired to mount therein.

4 represents a floor which is mounted within the open rear portion of the shield and serves as a support for the guns 3. As shown in Fig. 1, the floor has permanently formed on it or fixed to it suitable parallel ribs 4', and between these ribs the rear ends of the guns are fitted, whereby the parallelism of the guns is maintained. The guns are so constructed that the rear portion may be fixed to this floor so that the guns will all have their axes parallel and at such a distance apart that the size of the gun or other requirements will dictate.

The muzzles of the guns pass out through openings or ports 4' in the front of the shield, and these openings are preferably made below the apex or front edge of the shield, so as to be little exposed to projectiles from the front.

The mechanism for firing the guns consists of hammers, as at 5, and these may be actuated by cams 6, mounted upon a shaft 7, journaled transversely with relation to the guns and having gears, as at 8, and a crank or equivalent means for turning said gears, as shown at 9, so that when the guns are properly trained and ready to fire it is only nec-

essary to turn the crank, when all the guns will be fired at once. It will be understood that the firing mechanism may be contained within or protected by the shield. The shield itself is journaled upon or in line with the shaft or axis 7, so that whatever changes may be made in the position of the shield the gears will remain in mesh and the firing mechanism will always be in the proper position whether the shield and guns be elevated or depressed. 60

10 is a frame of any suitable description, here shown in the form of a heavy yoke with upturned ends, in which the shaft 7 and shield-bearings are journaled and turnable.

11 is a segment fixed to the lower part of the shield, and 12 is a worm-gear the shaft of which is journaled so that the gear engages with the segment, and by means of a hand-wheel or other convenient mechanism, as at 13, the worm may be turned and the segment 70 advanced to either raise or depress the front of the shield and with it the guns which are mounted therein.

The yoke or frame 10 has fixed to it a segment-gear 14, this segment standing vertically 8c and extending down through another frame 15, with relation to which it is movable.

The center or bearing 16, about which the frame 10 is turnable, is the horizontal axis of the segment 14, and by means of a worm 85 or pinion engaging the segment 14 and actuated by a crank or equivalent means, as at 18, the frame 10, and with it the guns, may be tilted to any desired angle. Thus if the machine is standing upon a level and it is designed 90 to sweep a hillside or inclined surface the shield and guns may be tilted until they are substantially parallel with the hillside, or if the machine stands upon inclined ground and the ground to be swept by the guns is comparatively level or of a different inclination the shield and guns may be tilted in conformity with the surface.

The frame 15 has a vertical axis central with a gear 19, which gear is mounted upon the carriage A, and by means of a worm 20, actuated by a hand-wheel or equivalent device 21, the frame 15, and with it the frame 10, the shield, and the gun, may be turned around the vertical axis, so as to swing the guns to any 105 desired horizontal radius of operation.

Having thus described my invention, what I claim, and desire to secure by Letters Patent, is—

1. A gun-mount comprising a shield con-

- vergent at the front, open at the rear, a floor within said shield, a plurality of guns mounted parallel with each other within the shield having their muzzles projecting through ports in the lower part of said shield, a support in which the shield is journaled, mechanism by which the shield is turnable about its journals to elevate or depress the guns, and means for maintaining the parallelism of the guns said 5 means comprising ribs permanent with the floor and between which the rear ends of the guns are fitted.
2. In a gun-mount, a forwardly-convergent shield open at the rear, a floor within said 10 shield, a frame or yoke in which said shield is journaled, mechanism by which it is tilt-able in a vertical plane, a plurality of guns mounted parallel with each other and mov- 15 able in unison with the shield, said floor hav- 20 ing permanent parallel ribs between which the rear ends of the guns are fitted, ports

through the lower part of the shield through which the muzzles of the guns project.

3. In a gun-mount, a shield convergent to the front, open at the rear, a yoke or frame having upturned ends in which the ends of the shield are journaled, a floor within the shield having parallel ribs between which the rear ends of the guns are fitted whereby the parallelism of the guns is maintained, mechanism 25 by which the shield may be tilted in a vertical plane, and mechanism by which the yoke and shield may be tilted in a vertical plane transverse to the first-named plane.

In testimony whereof I have hereunto set 30 my hand in presence of two subscribing witnesses.

MICHAEL C. TAYLOR.
